UNITED STATES PATENT OFFICE.

JOHN SINKOVICH, OF YOUNGSTOWN, OHIO.

RAIL JOINT AND FASTENER.

1,328,695.

Specification of Letters Patent. Patented Jan. 20, 1920.

Application filed July 23, 1918. Serial No. 314,096.

To all whom it may concern:

Be it known that I, JOHN SINKOVICH, a citizen of the United States, residing at Youngstown, in the county of Mahoning and State of Ohio, have invented certain new and useful Improvements in Rail Joints and Fasteners, of which the following is a specification.

The primary object of the present invention resides in the provision of an improved construction in rail chairs in which the chair for supporting the rail is interlocked with the supporting tie and locked to the rail whereby creeping movement of the rail longitudinally of the tie and transversely of the road bed is obviated.

A further object of the invention is to provide an improved form of rail fastener having an interlocked connection with the tie and having arms detachably connected thereto for engagement with the rails, the fasteners coöperating with the rail chair to assist in supporting the rail.

With the above objects in view and others that will become apparent as the nature of the invention is better understood, the same consists in the novel construction, combination and arrangement of parts to be herein-after more fully described and then claimed, reference being had to the accompanying drawings by like characters designating corresponding parts throughout the several views, in which,

Figure 1 is a top plan view of a portion of a railroad track constructed in accordance with the present invention, there being illustrated the rail fasteners on one tie and a rail chair on the other tie,

Fig. 2 is a transverse sectional view of a tie with the rail supported thereon shown in side elevation and partially in section, illustrating the fastening bar embedded in the tie with the rail engaging clamps carried thereby,

Fig. 3 is a cross sectional view of the rail with the tie for supporting the same in side elevation, illustrating one of the clamps carried by the rail fastening block,

Fig. 4 is a view similar to Fig. 3 showing the form of clamp employed at the curved portions of the track in which the clamp has a rail web engaging portion,

Fig. 5 is an end elevational view of the rail chair with the tie supported therein shown in section,

Fig. 6 is a side elevational view of the

same showing the hinge connections between parts of the rail chair,

Fig. 7 is a perspective view of the rail chair removed from the tie, and

Fig. 8 is a perspective view of the rail locking block removed from the tie.

Referring more in detail to the accompanying drawings, there is illustrated in Fig. 1, a pair of spaced ties 10 for supporting the rails 11, the adjacent ends of which rails are supported upon one tie by the chair 12 and retained in position on the other tie by the clamps 13, the clamps 13 holding the rail immovable relative to the tie while the chair 12 holds the meeting ends of the rail immovable relative thereto and to the supporting tie.

The rail engaging clamps 13 together with the clamp block are shown more clearly in Figs. 2, 3, 4 and 8 and comprise in detail the formation of a dove-tailed transverse socket 14 in the upper sides of the ties 10 into which the wedge-shaped blocks 15 are received, threaded projections 16 being carried by the ends of the block 15 upon which the clamps 13 are received, while block 15 is held immovable vertically by the tie 10. Each clamp includes a base portion 17 having a rail base engaging flange 18 extending above the tie for engagement with the rail as illustrated in Fig. 3 and when so positioned a lock nut 19 is threaded on the projecting end of the portions 16 of the block to retain the clamps in operative position on the blocks relative to the rails.

Another form of clamp is shown in Fig. 4 and in this form of the invention the clamp is especially designed for use upon the curved portions of a railway track, the clamp 13 having the usual base portion 17 for reception on the threaded projecting ends 16 of the blocks while a rail web engaging portion 20 is carried thereby for purposes of strengthening and bracing the rail at the point that receives the greatest strain. With this form of rail fastener wherein the block is embedded in the tie and interlocked therewith when combined with the clamps herein illustrated, the rail is securely held upon the tie immovable relative thereto and with the manner of locking the clamps in position liability of the rail engaging clamps becoming loosened is greatly reduced.

The chair 12 shown in Fig. 1 is illustrated in detail in Figs. 5 and 7 and comprises a base plate portion 21 having a central de-

pending wedge-shaped portion 22 defining a similar recess 23 for purposes presently to appear. One edge of the base plate 21 carries a rail base engaging flange 24 formed rigidly and integrally therewith while the opposite edge of the plate 21 has a rail base engaging plate 25 hinged thereto as at 26 while threaded bolts 27 are hinged as at 28 to the free edge of the plate 25. The tie 10 is provided with an enlarged wedge-shaped recess 14' into which the member 22 is received as illustrated in Fig. 5 while the base plate 21 of the chair is countersunk in the upper face of the tie as at 10'. In this position a block 15' of wedge formation is inserted in the socket 23 to support the central portion of the rail 11 while in this instance, the threaded ends 16 of the block may be removed. As illustrated in Fig. 5 the rail 11 rests upon the base plate 21 of the chair 12 while the threaded bolts 27 project through openings 29 in adjacent rail web portions and through a fish plate 30 at the opposite sides of the web portions while lock nuts 31 are received on the projecting ends thereof. With this construction of chair, the chair is interlocked with the tie while the rail ends are securely locked within the chair 12 and held immovable.

30 While there is herein shown the preferred embodiment of the invention it is to be understood that various changes may be made in the details of construction of the several parts when the device is operatively constructed, such as will fall within the scope of the subject matter claimed.

What I claim as new is:—

1. A rail chair comprising in combina-

tion with a tie having a wedge-shaped socket therein, a base plate, a depending wedge-shaped portion carried thereby for reception in the tie recess, a block in the depending portion of said base plate upon which a rail is adapted to seat, an integral flange carried by one side of said base plate, a plate hinged to the other side of said base plate, threaded bolts hinged to the free swinging end of the last named plate, meeting rail ends having openings in the web portions thereof seated upon the base plate and said block with the threaded bolts projecting through said openings, a fish plate upon the opposite side of said rail webs through which the bolts are adapted to project and lock nuts upon the projecting ends of said bolts.

2. A device of the class described comprising in combination with a tie having a wedge-shaped recess, a rail chair embodying a depending portion seated in said recess, a wedge-shaped block within said depending portion, meeting rail ends seated upon the base plate and the block, rail engaging members carried by the base plate, bolts carried by one of said rail engaging members adapted for passing through the web portions of the rails, and lock nuts received on the projecting ends thereof.

3. A rail chair comprising a base plate, a depending portion centrally carried thereby, an integral flange formed at one edge of the base plate, a plate hinged to the other edge of the base plate, and rail engaging bolts carried by the free edge of the last named plate.

In testimony whereof I affix my signature. 75
JOHN SINKOVICH.
